HYDROTHERAPY BATH UNIT

Frank C. Bascomb and Erna Mayer, Chicago, Ill., assignors to Boulevard Electronics, Inc., a corporation of Illinois

Filed Dec. 26, 1963, Ser. No. 77,933

Term of patent 14 years

(Cl. D83—1)

FIG. 1 is a side elevational view of a hydrotherapy bath unit, showing our new design.

FIG. 2 is a top view thereof.

FIG. 3 is an end view looking at same from the right of FIG. 2.

FIG. 4 is a view taken on lines 4-4 of FIG. 1, and FIG. 5 is a view taken on lines 5-5 of FIG. 1.

The main housing on the opposite side is similar to that shown in FIG. 1. The end of the housing as viewed from the left of FIG. 2 is plain.

We claim:

The ornamental design for a hydrotherapy bath unit, as shown and described.
